1.8: Right

1.9: Top

The presented item is a table football playing figure. The playing figure consists of two parts, a figure and a base, which are permanently joined to form a single unit. The figure is made of a truncated cone-shaped hollow body, open at the top and firmly connected to the base at the bottom. The hollow design of the figure being a crucial design feature. The base has the shape of a hemisphere with a flat contact surface. The base is designed to be hollow, enabling the figure to be inserted deeply. The figure and base are defined by their shape, not by their print or color.
